UNITED STATES PATENT OFFICE.

AXEL HERMAN STAF, OF PROVIDENCE, RHODE ISLAND, ASSIGNOR TO GORHAM MANUFACTURING COMPANY, OF PROVIDENCE, RHODE ISLAND, A CORPORATION OF RHODE ISLAND.

DESIGN FOR A HANDLE FOR SPOONS, FORKS, OR SIMILAR ARTICLES.

49,287.

Specification for Design.

Patented June 27, 1916.

Application filed May 11, 1916. Serial No. 96,929. Term of patent 14 years.

To all whom it may concern:

Be it known that I, AXEL HERMAN STAF, a citizen of the United States, residing at Providence, in the county of Providence and State of Rhode Island, have invented a new, original, and ornamental Design for Handles for Spoons, Forks, or Similar Articles, of which the following is a specification, reference being had to the accompanying drawings, forming part thereof.

Figure 1 is a view of the obverse side of the handle, showing my design. Fig. 2 is a

view of the reverse side of the handle, showing my design. Fig. 3 is a sectional view of a portion of the handle on the line 3—3 of Fig. 1.

I claim—

The ornamental design for a handle for spoons, forks or similar articles, as shown.

AXEL HERMAN STAF.

Witnesses:

ADA E. HAGERTY,
J. A. MILLER.
